US0D1018455S

(12) **United States Design Patent** (10) **Patent No.:** **US D1,018,455 S**
(45) **Date of Patent:** **** Mar. 19, 2024**

(54) **DOCKING STATION CANISTER**

(71) Applicant: **iRobot Corporation**, Bedford, MA (US)

(72) Inventors: **Calvin Jinwon Lee**, Nashua, NH (US); **Ryan Mercier**, Boston, MA (US); **Rick Hoobler**, Waltham, MA (US); **Insun Hong**, Concord, MA (US)

(73) Assignee: **iRobot Corporation**, Bedford, MA (US)

(**) Term: **15 Years**

(21) Appl. No.: **29/857,584**

(22) Filed: **Oct. 24, 2022**

Related U.S. Application Data

(63) Continuation of application No. 29/746,570, filed on Aug. 14, 2020, now Pat. No. Des. 969,429.

(51) **LOC (14) Cl.** **15-05**

(52) **U.S. Cl.**

USPC **D32/31**; D13/118

(57) **CLAIM**

The ornamental design for a docking station canister, as shown and described.

DESCRIPTION

FIG. 1 is a top, front, left perspective view of a docking station canister, showing our new design;

FIG. 2 is a front view thereof;

FIG. 3 is a rear view thereof;

FIG. 4 is a right side view thereof;

FIG. 5 is a left side view thereof;

FIG. 6 is a top view thereof; and,

FIG. 7 is a bottom view thereof.

The broken lines depict portions of the docking station canister that form no part of the claimed design.

1 Claim, 7 Drawing Sheets
